UNITED STATES PATENT OFFICE.

SAMUEL FARON, OF PAHALA, KAU, HAWAII.

DIFFUSION APPARATUS.

SPECIFICATION forming part of Letters Patent No. 480,571, dated August 9, 1892.

Application filed April 12, 1892. Serial No. 428,811. (No model.)

To all whom it may concern:

Be it known that I, SAMUEL FARON, of Pahala, Kau, Hawaiian Islands, have invented a new and Improved Apparatus for Extracting Cane-Juice, of which the following is a full, clear, and exact description.

My invention is an improvement in that class of apparatus for extracting juice from sugar-cane in which the cane is subjected to pressure by successive sets of rolls and the light or thin juice obtained by the last set of rolls is carried back and mingled with the denser and heavier juice extracted by the first set of rolls.

15 The invention is embodied in the construction, arrangement, and combination of parts, as hereinafter described and claimed.

Reference is to be had to the accompanying drawings, forming a part of this specification, 20 in which similar letters of reference indicate corresponding parts in both the figures.

Figure 1 is a sectional side elevation of the apparatus, and Fig. 2 is a plan view of the same.

25 The cane-juice extractor is provided with a series of grinding-mills A, B, C, and D, of which the grinding-mill A is preferably provided with three rollers, while the others contain only two. The several mills are connected with each other by suitably-constructed

30 elevators E E' E², so that the cane is transmitted from one to the other, to be finally discharged from the last mill D through an outlet F. A spray of hot water can be introduced 35 upon the discharge of the mill C by means of a suitably-arranged pipe G, connected with the source of water-supply. The juice from the several mills passes into the outlets H, H', H², and H³, and connection is established be-

40 tween the outlet H³ and a perforated pipe I, extending across the discharge of the mill B, as is plainly shown in Fig. 1, so that the juice from the said outlet H³ can pass through the pipe I by suitable pumping machinery J, to 45 be discharged upon the discharge of the mill B.

The operation is as follows: The cane is first passed through the mill A and then transmitted by the elevator E to the mill B. The juice pressed out of the cane by the mills A and B 50 collects in the outlets H and H', respectively, and the cane after leaving the mill B usually

contains about fifteen to twenty per cent. of cane-juice. The cane then passes up the elevator E' and through the mill C, to be again subjected to pressure. After passing through 55 the mill C a spray of hot or cold water equal to from three to four times the quantity of the normal juice contained in the bagasse from the mills A and B is now let into the bagasse by the pipe G, thus reducing the 60 density of the juice at that point from 10° to about 1.5° Baumé. A portion of this juice, equal to the amount of water used, after passing through the mill D is pumped or brought by other means back and goes in a spray 65 upon the bagasse coming from the mill B by passing through the pipe I upon the bagasse, thus reducing a portion of the juice in the bagasse at that point from 10° to about 4.37° Baumé. The bagasse containing this juice now 70 passes by the elevator E' to the mill C, where a quantity equal to the amount of light juice brought from the mill D goes to the boiling-house, and the portion left in the bagasse now passes upon the mill D after receiving a spray 75 of water through the pipe G, so that the juice in the bagasse is reduced at this point from 4.37° to 1.09° Baumé. This operation is continued, so that in a few minutes the juice in the bagasse going from the mill D to the furnace 80 is reduced to a density of about .76° Baumé. Bagasse used as a fuel and containing this quantity of saccharine matter more than compensates for the loss of the sugar in securing better quality of bagasse as a fuel. 85

In other apparatus of this particular class the juice expressed from all the mills of a set, save the first, has been elevated into a tank by means of a pump and suitable pipes connected with it. Thus as many tanks and 90 pumps were required as there were mills or sets of rolls, save one, which involved corresponding expense, as well as rendered the apparatus very bulky. By my improvement I dispense with all such tanks and require but one 95 pump, since all the receiving vats or outlets are directly connected by pipes, and the pump is attached to that one of the pipes which extends between the last mill and the adjacent one, whence a discharge-pipe leads directly 100 to one of the first mills of the series.

Having thus described my invention, I

claim as new and desire to secure by Letters Patent—

In a cane-juice-extracting apparatus of the character hereinbefore described, the combination, with the series of mills A B C D and elevators and troughs arranged between them for transferring the bagasse from one to another, of the juice receivers and outlets H H' H² H³, the horizontal pipes connecting all said

outlets, a pump J, attached to one of said 10 pipes at a point between the last two outlets H² and H³ of the series and leading thence directly to the mill B, as shown and described.

SAML. FARON.
